UNITED STATES PATENT OFFICE.

ISAAC W. LITCHFIELD, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

AUTOMATIC SWITCH FOR PNEUMATIC-TUBE APPARATUS.

968,577.

Specification of Letters Patent. Patented Aug. 30, 1910.

Application filed November 28, 1906. Serial No. 345,456.

To all whom it may concern:

Be it known that I, ISAAC W. LITCHFIELD, of Boston, in the county of Suffolk and State of Massachusetts, have invented certain new and useful Improvements in Automatic Switches for Pneumatic-Tube Apparatus, of which the following is a specification.

My invention relates to automatic switches for pneumatic despatch tube apparatus and its object is to provide a simple and effective device for diverting or switching the carriers through the different branch tubes of said apparatus to their proper destination.

In the accompanying drawings which illustrate a construction embodying my invention, Figure 1 is a vertical section showing a selective carrier in operating contact with the switching mechanism. Fig. 2 is a side elevation of the device. Fig. 3 is a bottom plan view of Fig. 1 with valve and receiver removed.

Like letters of reference refer to like parts throughout the several views.

B represents a casing connecting at each end with the main or transmission tube A.

C represents a branch tube connecting with the casing B and controlled by the valve D pivoted at D'. Pivoted in the chamber E of the casing B at E' is a switch arm E² normally held in the full line position as shown in Fig. 1 by means of a helical spring E³. Pivoted to the switch arm E² by the pin E⁴ is a selective trigger E⁵ which is adapted to maintain a normal position as shown in full lines Fig. 1. The movement of the trigger E⁵ is limited in relation to the switch arm E² by a pin or stop E⁶ fixed to said switch arm. At the rear of the switch arm E² mounted in the chamber E and fixed

to casing B is an arm F having a laterally projecting stop or member F' adapted to cooperate in certain relative positions of the switch arm E² and the trigger E⁵ with a laterally projecting lip E⁷ on the trigger E⁵.

Opposite the switching mechanism is a chamber G in which is pivoted at one end on the pin G' a lever G², the opposite end of said lever G² projecting into the path of and adapted to engage and hold the carriers in engagement with the switching mechanism. Tension is applied to the lever G² by a helical spring G⁴ mounted over the pin G', one end of said spring fixed to the lever G², the opposite end being adapted to be

adjusted in the notches in the rack G³ to 55 obtain the desired tension.

The operation is as follows: A selective carrier having a projection on either end as shown in dotted lines Fig. 1 traveling through the transmission tube A arrives opposite the switch arm E² which is held in the normal or diverting position by a spring E³ as heretofore described. The projection on the carrier engages the selective trigger E⁵ which causes the lip E⁷ to be lifted to 60 the position shown in dotted lines Fig. 1, engaging the lip F' before the buffer of the carrier strikes the switch arm E². The switch arm E² is now locked in the diverting position preventing the movement of 65 the switch arm E² by the impact of the carrier. In the meantime, the carrier is held in engagement with the switching mechanism by the tension of the lever G². The carrier is now switched into the branch tube C 70 through the valve D. After the passage of the carrier, the switching mechanism immediately resumes its normal or unlocked position. If an ordinary carrier without the selective projections is in transit in the tube 75 A, the buffer on the carrier engages the switch arm E² before striking the selective trigger E⁵ thereby causing the switch arm 80 E² to swing back to the position shown in dotted lines Fig. 1 and permitting the carrier to pass directly through the main transmission tube A. In the meantime, the carrier is held in operating engagement with the switch arm E² by means of the tension 85 of lever G². After the passage of the carrier, the switching mechanism resumes its 90 normal position.

Having thus described the nature of my invention and set forth a construction embodying the same, what I claim as new and 95 desire to secure by Letters Patent of the United States is:

1. In an automatic switch for pneumatic despatch apparatus, switching means adapted to permit the passage of an ordinary carrier, locking means adapted to be operated by a selective carrier for locking said switching means in a diverting position for switching said carrier, and means in the path of the traveling carriers for holding said carriers in operating contact with said switching means.

2. In an automatic switch for pneumatic

despatch apparatus, switching means adapted to permit the passage of an ordinary carrier, locking means adapted to be operated by a selective carrier for locking said switching means in a diverting position for switching said carrier, and yielding means for holding said carriers in operating contact with said switching means.

3. In an automatic switch for pneumatic despatch apparatus, switching means normally held in diverting position and adapted to permit the passage of an ordinary carrier, means adapted to be operated by a selective carrier for locking said switching means in diverting position, and means in the path of the traveling carriers for holding said carriers in operating position.

4. In an automatic switch for pneumatic

despatch apparatus, switching means adapted to permit the passage of an ordinary carrier, locking means adapted to be operated to lock said switching means in a diverting position, projecting means located on the buffer of a selective carrier and adapted to operate said locking means to switch said selective carrier, and a spring actuated lever in the path of the traveling carriers for holding said carriers in operating contact with said switching means.

In testimony whereof, I have signed my name to this specification in the presence of two subscribing witnesses.

ISAAC W. LITCHFIELD.
